United States Patent

Des. 236,018
Patented July 22, 1975

236,018

SELF-WATERING PLANTER

June H. Swift, P.O. Box 28012, and John A. Swift, 2740
Mayhew, both of Dallas, Tex. 75228

Filed May 21, 1973, Ser. No. 362,536

Term of patent 14 years

Int. Cl. D11—02

U.S. Cl. D35—3 A

FIG. 2

FIG. 1

FIG. 3

FIG. 4

FIG. 1 is a perspective view of a self-watering planter showing our new design;

FIG. 2 is a top plan view thereof;

FIG. 3 is a side elevation thereof; and

FIG. 4 is a bottom plan view thereof.

We claim:

The ornamental design of a self-watering planter, as shown and described.
